UNITED STATES PATENT OFFICE.

JOHN ROBSON, OF WESTMINSTER, LONDON, ENGLAND, ASSIGNOR TO THE VARIABLE SPEED GEAR LIMITED, OF WESTMINSTER, ENGLAND.

VARIABLE-DELIVERY PUMP OR FLUID-PRESSURE MOTOR.

1,147,893.

Specification of Letters Patent.

Patented July 27, 1915.

Application filed November 8, 1913. Serial No. 799,877.

To all whom it may concern:

Be it known that I, JOHN ROBSON, a subject of the King of Great Britain, residing at Broadway Court, Westminster, in the county of London, England, have invented certain new and useful Improvements in Variable-Delivery Pumps or Fluid-Pressure Motors, of which the following is a specification.

- 10 This invention relates to variable delivery pumps or fluid pressure motors of the kind comprising a cylinder barrel having a number of cylinders for the reception of pistons provided with piston rods that are pivotally connected to the pistons and to a plate or disk which is carried by a tilting box the displacement of which (in the case of the pump) with respect to the barrel causes the flow of fluid from the pump to be varied, 15 and in the case of the motor causes the speed thereof to be varied. The said tilting box of the pump has in some cases been adjusted by means of a screw threaded shaft carried in bearings in the pump casing and 20 engaging with a nut having trunnions that carry guide blocks, these guide blocks being slidably disposed between horns or brackets formed on the tilting box.

It has been found that these horns or brackets are liable to bend or break especially when the pump is operating under high pressures, and the chief object of the present invention is to so construct the mechanism for displacing the tilting box 35 that the said horns or brackets can be dispensed with.

According to this invention the tilting box is provided with a projection, preferably of circular cross section, which loosely 40 carries a bearing block rotatably connected to a reciprocating member, the movement of which by any suitable means effects the displacement of the tilting box.

In order that the said invention may be 45 clearly understood and readily carried into effect the same will be described more fully with reference to the accompanying drawings, in which:—

Figure 1 is a longitudinal section showing a constructional form of our improvements. Fig. 2 is a transverse section taken approximately on the line 1—1 of Fig. 1. Fig. 3 is a plan of a portion of Fig. 1, and Fig. 4 is a section showing a slightly modified constructional form.

A is the casing of the pump or motor and B is the tilting box.

B' represents the projection on the tilting box, C the bearing block and C' the reciprocating member.

In the example shown, the bearing block C has convex surfaces which engage with corresponding concave surfaces on the reciprocating member C'. This member is in the form of a rectangular crosshead suitably guided between ribs A' formed on the casing A, and having a screw threaded rod or spindle C² integral therewith or connected thereto. The said ribs are arranged parallel to the axis of the screw threaded rod or spindle C² and serve to prevent angular movement of the said rod or spindle and to take the side thrust which occurs upon the bearing block C during the displacement of the tilting box B. The said screw-threaded rod or spindle engages with a nut C³ which is carried by the casing A in such manner that it can rotate but cannot move axially. The said nut projects beyond the casing and is adapted to receive a handle by means of which it can be rotated to effect the reciprocating movement of the rod or spindle. Instead of operating the nut directly by means of a handle, a servo-motor, solenoid or other suitable device may be employed. Suitable thrust washers or bearings C⁴ are interposed between a collar c³ on the nut C³ and a shoulder a of the casing A, and between the said collar and a removable bearing A² in which the nut is mounted. The latter bearing is carried by the casing and is preferably provided with a stuffing box of any suitable construction. In the example shown, the nut C³ is recessed to receive a leather lace c⁴ which lies in contact with the bearing A².

The bearing block C may, as shown in Fig. 4, be made in two halves and the cross-head C' may be provided with a screw c' for the purpose of adjusting the half bearings to compensate for wear. The aforesaid projection B' on the tilting box may be situated in any convenient position thereon, and the axis of the screw threaded rod or spindle C² may be either normal, parallel, or at any inclination to the longitudinal axis of the pump—i. e. to the axis of the driving shaft.

The herein referred to pump and motor generally constitute the pump and motor

units of a variable hydraulic transmission gear.

What I claim and desire to secure by Letters Patent of the United States is:—

- 5 1. In mechanism for varying the delivery of a fluid pump or the speed of a fluid pressure motor, the combination with a tilting member, of a projection on said member, a bearing block loosely carried by and surrounding said projection, a reciprocatory member rotatably connected to said bearing block and means for displacing said reciprocatory member.
- 10 2. In mechanism for varying the delivery of a fluid pump or the speed of a fluid pressure motor, the combination with a casing of the pump or motor, and a tilting member carried by the casing, of a projection on said member, a bearing block loosely carried by and surrounding said projection, a reciprocatory member rotatably connected to said bearing block, guides in the casing for said reciprocatory member and means for displacing the latter member.
- 15 3. In mechanism for varying the delivery of a fluid pump or the speed of a fluid pressure motor, the combination with a casing of the pump or motor, and a tilting member carried by the casing, of a projection on said member, a bearing block loosely carried by said projection and having convex surfaces, a reciprocatory member rotatably connected to said bearing block, guides in the casing for said reciprocatory member and means for displacing the latter member.
- 20 4. In mechanism for varying the delivery of a fluid pump or the speed of a fluid pressure motor, the combination with a casing of the pump or motor, and a tilting member carried by the casing, of a projection on said member, a bearing block loosely carried by said projection and having convex surfaces, a crosshead engaging with said convex surfaces, guides in the casing for said crosshead and means for displacing the crosshead.
- 25 5. In mechanism for varying the delivery of a fluid pump or the speed of a fluid pressure motor, the combination with a casing of the pump or motor, and a tilting member carried by the casing, of a projection on said member, a bearing block loosely carried by said projection and having convex surfaces, a crosshead engaging with said convex surfaces, guides in the casing for said crosshead, a screw threaded shaft integral with the crosshead, a screw threaded shaft integral with the crosshead, a rotary nut engaging with the screw threaded shaft, a removable bearing carried by the casing and carrying said nut, a collar on said nut, a projection on the casing and thrust washers interposed between the bearing and the collar and between the collar and the projection.
- 30 6. In mechanism for varying the delivery of a fluid pump or the speed of a fluid pressure motor, the combination with a casing of the pump or motor, and a tilting member carried by the casing, of a projection on said member, a bearing block made in two halves loosely carried by said projection and having convex surfaces, a crosshead engaging with said convex surfaces, guides in the casing for said crosshead, a screw threaded shaft integral with the crosshead, a rotary nut engaging with said screw threaded shaft, a removable bearing carried by the casing and carrying said nut, a collar on said nut, a projection on the casing and thrust washers interposed between the bearing and the collar and between the collar and the projection.
- 35 7. In mechanism for varying the delivery of a fluid pump or the speed of a fluid pressure motor, the combination with a casing of the pump or motor, and a tilting member carried by the casing, of a projection on said member, a bearing block loosely carried by said projection and having convex surfaces, a crosshead engaging with said convex surfaces, guides in the casing for said crosshead, a screw threaded shaft integral with the crosshead, a rotary nut engaging with said screw threaded shaft, a removable bearing carried by the casing and carrying said nut, a collar on said nut, a projection on the casing and thrust washers interposed between the bearing and the collar and between the collar and the projection.
- 40 8. In mechanism for varying the delivery of a fluid pump or the speed of a fluid pressure motor, the combination with a casing of the pump or motor, and a tilting member carried by the casing, of a projection on said member, a bearing block loosely carried by said projection and having convex surfaces, a crosshead engaging with said convex surfaces, guides in the casing for said crosshead, a screw threaded shaft integral with the crosshead, a rotary nut engaging with said screw threaded shaft, a removable bearing carried by the casing and carrying said nut, a collar on said nut, a projection on the casing and thrust washers interposed between the bearing and the collar and between the collar and the projection.
- 45 9. In mechanism for varying the delivery of a fluid pump or the speed of a fluid pressure motor, the combination with a casing of the pump or motor, and a tilting member carried by the casing, of a projection on said member, a bearing block loosely carried by said projection and having convex surfaces, a crosshead engaging with said convex surfaces, guides in the casing for said crosshead, a screw threaded shaft integral with the crosshead, a rotary nut engaging with said screw threaded shaft, a removable bearing carried by the casing and carrying said nut, a collar on said nut, a projection on the casing and thrust washers interposed between the bearing and the collar and between the collar and the projection.
- 50 10. In mechanism for varying the delivery of a fluid pump or the speed of a fluid pressure motor, the combination with a casing of the pump or motor, and a tilting member carried by the casing, of a projection on said member, a bearing block loosely carried by said projection and having convex surfaces, a crosshead engaging with said convex surfaces, guides in the casing for said crosshead, a screw threaded shaft integral with the crosshead, a rotary nut engaging with said screw threaded shaft, a removable bearing carried by the casing and carrying said nut, a collar on said nut, a projection on the casing and thrust washers interposed between the bearing and the collar and between the collar and the projection.

carried by the casing, of a projection on said member, a bearing block loosely carried by said projection and having convex surfaces, a crosshead engaging with said convex surfaces, guides in the casing for said crosshead, a screw threaded shaft integral with the crosshead, a rotary nut engaging with the screw threaded shaft.

6. In mechanism for varying the delivery of a fluid pump or the speed of a fluid pressure motor, the combination with a casing of the pump or motor, and a tilting member carried by the casing, of a projection on said member, a bearing block loosely carried by said projection and having convex surfaces, a crosshead engaging with said convex surfaces, guides in the casing for said crosshead, a screw threaded shaft integral with the crosshead, a rotary nut engaging with said screw threaded shaft, a removable bearing carried by the casing and carrying said nut, a collar on said nut, a projection on the casing and thrust washers interposed between the bearing and the collar and between the collar and the projection.

7. In mechanism for varying the delivery of a fluid pump or the speed of a fluid pressure motor, the combination with a casing of the pump or motor, and a tilting member carried by the casing, of a projection on said member, a bearing block made in two halves loosely carried by said projection and having convex surfaces, a crosshead engaging with said convex surfaces, guides in the casing for said crosshead, a screw threaded shaft integral with the crosshead, a rotary nut engaging with said screw threaded shaft, a removable bearing carried by the casing and carrying said nut, a collar on said nut, a projection on the casing and thrust washers interposed between the bearing and the collar and between the collar and the projection.

In testimony whereof I affix my signature in presence of two witnesses.

JNO. ROBSON.
